ABSTRACT

An exterior door incorporates at least one moving glass insert or sash slidable in first and second spaced apart tracks. An end of the insert is coupled to an end of a spring biased rolled screen. As the insert moves from the roll, the screen is extracted therefrom providing a continuously variable screened region in the door. The insert can be positioned using a counterbalance or spaced apart latchable locations in the door.

DOOR WITH VARIABLE LENGTH SCREEN

This application is a utility application claiming the benefit of the earlier filing date of provisional application Ser. No. 60/310,557 filed Aug. 7, 2001.

FIELD OF THE INVENTION

The invention pertains to doors. More particularly, the invention pertains to doors having at least one slidable glass pane or panel with an extendable screen attached thereto.

BACKGROUND OF THE INVENTION

Storm doors which incorporate panes of glass and screens are known. Some forms of such doors include screens which are fixedly mounted to the frame of the door with sliding glass inserts. With these doors, the inserts usually can be locked into a plurality of vertical positions with spring loaded latches to expose varying degrees of screen. When the inserts are moved to their fully close position, such as during storms or in cold weather, a person looking at the door, must look through at least one pane of glass and the screen.

In other forms of doors, glass inserts or screen inserts are installed on the doors' frame depending on the season. In warmer weather the glass insert is removed and a screen insert is used in the frame. In cooler weather, the screen is removed and a glass insert is attached to the frame. With such doors, an individual looking at the door looks through either a pane of glass or a screen but not both.

One known door configuration provides a fixed screen with a counterbalanced insert. In this configuration, the insert is not latched at a selected position on its track. The counterbalance makes it possible to position the insert at any desired position on the track. However, when the insert is in its closed position, a person viewing the door must look through both the glass insert and the screen.

Patio door configurations are known which include sliding glass doors which can be opened or closed to provide access to a patio or a porch. Spring biased screen modules are known which can be attached to the patio door frame. These modules include horizontally retractable screens which can be extended across a patio door opening to exclude insects or other flying pests.

While the known doors are generally suitable for their intended purpose, they all suffer from one or more deficiencies in performance, convenience and ease of use. There continues to be a need for multi-season doors which provide convenient and easy to use screened openings during warmer drier weather while at the same time making it possible to easily close the screened area with a glass pane during cooler or wetter weather. Preferably such doors could be manufactured, at least in part, using techniques for manufacturing existing doors so as to benefit from the economies of scale that such manufacturing capabilities provide. Additionally, it would be preferable if such doors were easy to maintain and designed to be forgiving in the event that the screen is in need of replacement.

Numerous other advantages and features of the present invention will become readily apparent from the following detailed description of the invention and the embodiments thereof, from the claims and from the accompanying drawings.

BRIEF DESCRIPTION OF THE DRAWINGS

FIG. 1A is a front elevational view of a door in accordance with the present invention;

FIG. 1B is a top plan view of the door of FIG. 1A; FIG. 1C is a side view of the door of FIG. 1A; FIG. 2A is a rear elevational view of the door of FIG. 1A; FIG. 2B is a rear elevational view of an alternate door in accordance with the invention;

FIG. 3A is an exploded view of the door of FIG. 1A; FIG. 3B is a rear isometric view of the door of FIG. 1A; FIG. 4A is an exploded view of an alternate embodiment of the door of FIG. 1A;

FIG. 4B is a rear isometric view of the door of FIG. 4A; FIGS. 5A and B are side sectional views taken along plane 5A—5A of the door of FIG. 1A;

FIG. 5C is a sectional view taken along plane 5C—5C of the door of FIG. 1A; FIG. 5D is an enlargement of a portion of the section of FIG. 5C;

FIG. 5E is a sectional view taken along plane 5E—5E of FIG. 5A;

FIG. 5F is an enlarged partial view of a portion of the door of FIG. 1A illustrating details thereof;

FIG. 5G is an enlarged partial view illustrating details of an alternate embodiment of the door of FIG. 1A;

FIGS. 6A, 6B and 6C taken together are isometric views illustrating a process of engaging an extendable screen cloth with the jambs of the door of FIG. 1A;

FIGS. 7A—7C illustrate details of a replaceable screen module usable in the door of FIG. 1A;

FIG. 8 is a rear isometric view of the door of FIG. 1A illustrating aspects of removing and replacing the screen module;

FIG. 9 is an enlarged region of a portion of FIG. 8 illustrating additional details thereof;

FIG. 10 is a front elevational view of another door which embodies the invention;

FIG. 10A is a side section of the door of FIG. 10 taken along plane 10A—10A;

FIG. 11 illustrates an end sectional view of a plurality of alternate mechanisms for coupling a retractable screen to a movable door insert; and

FIG. 12 is a rear elevational view of another door in accordance with the present invention.

DETAILED DESCRIPTION OF THE PREFERRED EMBODIMENTS

While this invention is susceptible of embodiment in many different forms, there are shown in the drawing and will be described herein in detail specific embodiments thereof with the understanding that the present disclosure is to be considered as an exemplification of the principles of the invention and is not intended to limit the invention to the specific embodiments illustrated.

In one embodiment of the invention, an exterior door incorporates a replaceable screen module which includes an integral, spring biased, retractable screen which is coupled to a movable glass insert in the door. As the insert is moved from the screen, the screen is withdrawn from its retracted

position and extends along the frame of the door screening the otherwise open region from which the glass insert has moved. As the window sash or insert moves in the opposite direction toward the screen module, the screen is retracted into the module reducing the ventilation region available in the door.

FIGS. 1A—1C illustrate various views of a door 10 which embodies the present invention. The door 10 includes a

header 12a, two door jambs 12b, c and a sill 12d. The members 12a . . . d define a door frame with an interior region which in the door 10 includes a kick plate generally indicated at 14a, a lower pane or glass insert 14b, and an upper pane or glass insert 14c. Mullions 18a, b on the exterior side of the frame join jambs 12b, c.

In the door 10, the pane or insert 14b is fixedly mounted between the jambs 12b, c and above the kick plate 14a. The pane or insert 14c is mounted in tracks, discussed in more detail subsequently, for vertical motion generally in directions 16a, b relatively to insert 14b.

When the insert 14c is positioned at its uppermost location adjacent to header 12a, the door 10 is fully closed with two glass panes as one would use it in cool or wet weather. The pane or insert 14c can be moved, vertically, in direction 16b, away from header 12a thereby opening the upper portion of door 10 for ventilation.

A screen module 20, best seen in FIG. 7A can be coupled to the jambs 12b, c, header 12a or sill 12d. Module 20 carries a retracted screen which has a free end which carries an attachment member 22 which is coupled to an upper end of insert 14c. As the insert 14c is moved in the direction 16b, screen fabric or material 22-1 from the module 20 is extracted therefrom filling any gap or space between an upper end of insert 14c and header 12a.

Door 10 can thus, as described above, be converted from a storm door with two glass panes to a screen door simply by moving pane or insert 14c vertically downwardly. Where insert 14c is moved vertically downwardly to kick plate 14a, the extracted screen fills the entire area previously closed by pane 14c.

When the insert 14c is raised, direction 16a, the screen material 22-1 retracts into module 20 for storage. As discussed below, module 20 is removable for maintenance or replacement.

It will be understood that alternate configurations to the door 10 come within the spirit and scope of the present invention. For example, the screen module 20 can be mounted at or near the base 12d to provide an openable lower screened region. Alternately, instead of screening material, sheet plastic could be used in the module 20.

Members 12a-12d of the frame for the door 10 can be formed of metal, such as extruded aluminum, extruded or molded plastic, or partly or completely of a wood product. Inserts 14b, c need not include glass but could in fact be closed with translucent or transparent plastic material without departing from the spirit and scope of the present invention.

FIG. 2A is a rear elevational view of the door 10 illustrating the location of screen module 20 adjacent to header 12a. Screen module 20 is enclosed by a removable cover 24 which can be removed for purposes of maintenance and for replacing the module 20.

FIG. 2B illustrates an alternate embodiment, a wood core door 10-1 which incorporates screen module 20. The wood core door 10-1 can be formed with a wood-products core covered with either metal, such as aluminum, or cured resin such as vinyl. It will be understood that the screen module 20 is coupled to a sash or insert, comparable to the insert 14c, which moves vertically in tracks, as would be understood by those of skill, in the frame for the door 10-1.

FIGS. 3A and 3B are an exploded view of the door 10 and a rear isometric view thereof.

As illustrated in FIG. 3A, module 20 incorporates a spring or retractor assembly 26 which is carried in a hollow screen

roll or cylinder 28. The cylinder 28 rotates about retractor assembly 26 and pivot cap 28-1.

The module 20 is attached to the door so as to permit rotary motion thereof by brackets 30-1 and 30-2, best seen in FIGS. 7A-C. Screen roll 28 carries the coiled screen fabric 22-1 with attached connection member 22, best seen in FIG. 7B.

The spring assembly 26 exerts a substantially constant retracting force on the spring fabric on the roll 28 as the insert 14c is moved vertically in directions 16a, b. The screen material 22-1 is thus constantly under tension.

The insert 14c in door 10, is counterbalanced by counterbalancing mechanisms 36a, b carried by the insert 12a. The counterbalancing mechanisms 36a, b move with the insert 14a in the jambs 12b, c and are invisible to the user. Types of counterbalances include block and tackle balance, spiral balance and coil spring balance.

The counterbalances 36a, b make it possible to smoothly move the insert 14c in the direction 16a, b. The insert 14c can be positioned anywhere along its range of travel and will remain there until moved due to the forces exerted by the counterbalance mechanisms 36a, b.

FIGS. 4A, B illustrate an alternate embodiment, a door 10-2, which embodies the present invention. Those elements of door 10-2 which correspond to previously discussed elements of the door 10 have been assigned the same identification numerals. As an alternate to the counterbalance mechanisms 36a, b, the door 10-2 incorporates spring biased finger operable latches 38a, b which are carried by the insert 14c'. The latches extend laterally outwardly into slots in the jambs 12b', c' to lock the insert 14c' into a plurality of spaced apart vertical positions.

In the door 10-2, the insert 14c' can be moved vertically to a locking position, the movement will retract the screen 22-1 off of the roll 28 and filling the area of the door frame from which the insert 14c' has been moved. The mechanical latches 38a, b will lock the insert 14c' at the desired degree of openness in the frame of the door 10-2 desired.

In yet another embodiment, insert 14c can frictionally engage tracks in jambs 23b, c. The frictional forces will support insert 14c at any one of a variety of positions. In this embodiment, no counterbalances or latches are needed.

FIGS. 5A and 5B are sectional views taken along plane 5A—5A of FIG. 1A. The views of FIGS., 5A, B illustrate the relationship of various structural elements of the door 10 as the insert 14c moves from a fully closed position, FIG. 5A, to a partially open position, FIG. 5B. FIG. 5B illustrates the extended screen fabric 22-1.

FIG. 5C, a section taken along plane 5C—5C of FIG. 1A illustrates the insert tracks 52b, 52c which run axially along each of the jambs 12b, c. The insert 14c moves axially in and is retained within those tracks.

As illustrated in FIG. 5B, the insert 14c which is coupled to the screen fabric 22-1 moves axially in tracks 52b, c between insert 14b and mullion 18a. The screen end retaining member 22 is slidably received in a retaining feature 50 located at an upper end of the insert 14c.

Edges of the screen fabric 22-1 are confined in axial tracks 54-1, -2. These can be formed in jambs 12b, c.

FIG. 5D illustrates the counterbalance mechanism 36a, b which is carried by the insert 14c. Hence, insert 14c can be located at any vertical position on its range of travel as defined by the tracks 52b, 52c along the jambs 12b, c. When so positioned, the screen fabric 22-1, will be extended from the module 20 to the connector feature 50 to close the

opening in the frame of the door **10** left by moving the insert **14c** to a position closer to the kick plate **14a**.

FIG. 5D also illustrates the screen material **22-1**, illustrated in phantom, extended, as in FIG. 5B, extending between first and second weather stripping elements **54a** and **54b**. Weather stripping element **54a** extends axially along the respective jamb **12b, c** on each side of the door **10**. The weather stripping **54a** can be any form of weather stripping as would be known to those of skill in the art.

The weather stripping **54b** is different and unlike the weather stripping **54a**. The weather stripping **54b** is also positioned in an axially oriented slot which runs along the jambs **12b, c**.

Weather stripping **54b** is commercially available from Reddiplex Group PLC, Worcestershire, England under the trade name "MESHLOCK" and is formed with a mounting section **56-1** which slidably engages the respective slot in the jamb **12b, c**. The mounting section **56-1** carries a deflectable planar element **56-2** which extends from the mounting section **56-1** toward the weather stripping **54a** at a predetermined angle in a range of 15-75° relative to the plane of the screen.

The weather stripping **54a** acts to press the edge of the screen material **22-1** toward the MESHLOCK-type weather stripping **54b**, see FIG. 5F. This interaction provides a screen edge retention function. The fibers of the MESHLOCK weather stripping **54b** resist screen material **22-1** being pulled from between weather stripping **54a, b**, and the tracks **54-1, -2**.

It will be understood that other commercially available forms of weather stripping can be used instead of the MESHLOCK brand without departing from the spirit and scope of the invention.

It will be understood that while the MESHLOCK weather strip **54b** has been illustrated in FIGS. 5D and 5F as exhibiting an acute angle between the mounting section **56-1** and the screen retaining section **56-2**, other variations of MESHLOCK weather stripping could be used. Alternately as in FIG. 5C, the members **56-1', -2'** could be oriented at 90° to one another. In this embodiment, the track in which the mounting section **56-1'** would be located would be oriented at an appropriate angle, best seen in FIG. 5G, relative to the respective jamb **12b, c** to provide the desired interaction of pressing the screen material **22-1** between the weather stripping **54a, 54b'**.

FIGS. 6A, B and C taken together illustrate screen fabric or cloth **22-1** slidably engaging track **54-1**, similarly **54-2**, located in each of the jambs **12b, c** and which extend axially along the jamb. The end attachment feature **22** also slidably engages the track or slot **54-1, -2** on each of the jambs **12b, c**.

Though the screen cloth or material **22-1** may be forced out of the respective tracks **54-1, -2** in each of jambs by a laterally directed force, the screen attachment member **22** will continue to remain in each of the tracks. This is facilitated by the shape of the attachment member **22** which includes an end region **23** which extends into the respective slot **54-1, -2**.

In this instance, assuming that the screen cloth **22-1** has been forced from the respective track **54-1**, the upper insert **14c** can be moved to its fully closed position adjacent to header **12a** to retract the screen onto the screen roll **28**. In this circumstance, the attachment feature **22** is properly aligned to re-enter the tracks **54-1**. As the insert **14c** is moved away from the header **12a**, it will pull the attachment member **22** with it. The ends **23** of the attachment member

22 will enter the respective slots **54-1** pulling the screen cloth **22-1** with them and retracking the screen. Alternately, the attachment member **22** can exhibit a retracted condition, adjacent to the screen module **20** while continuing to remain in the tracks **54-1**.

Thus, as described above, if a force is exerted against the screen material **22-1** to pull it out of the side tracks **54-1** in each jamb, it is only necessary to reclose the insert **14c** to rewind the screen material **22-1** into a proper configuration so that it will be immediately re-extendable into the slots or tracks **54-1**.

FIGS. 7A, 7B and 7C illustrate additional details of the screen module **20**. The module **20** is supported adjacent to the header **12a** by brackets **30-1, -2**. Module **20** can be removably attached to the header, the sill or the jambs. The module **20** is removable from the brackets **30-1, -2** for maintenance and/or replacement once the cover **24** has been removed from the respective door.

FIG. 8 illustrates additional details of removing and replacing the module **20**. The connecting member **22** can be slid from the retaining feature **50** of the insert **14c** as illustrated in FIGS. 8 and 9. When so-slid from the retaining feature **50**, the entire module **20** can be replaced. Replacement involves attaching the connecting member of the new module to the attachment feature **50** by reversing the process illustrated in FIGS. 8 and 9. The screen roll **28** and screen fabric **22-1** can then be reattached brackets such as brackets **30-1, -2** in the header of the respective door. The cover **24** can be replaced. Moving the insert **14c** vertically toward and away from the header will cause the screen fabric **22-1** of the replacement module to retract and extend as expected.

FIGS. 10, 10A and 10B illustrate a door **60** which has a header **62a**, jambs **62b, c** and a sill **62d**. The door **60** includes insert **64a** which is movable vertically toward the header **62a** and away therefrom toward the sill **62d**. The insert **64a** can be supported by counterbalances, latches or frictional forces as discussed above relative to the door **10**.

The door **60** carries a screen module **66**, best illustrated in FIG. 10A. A free end of the screen of the screen module **66** is coupled to an upper end of insert **64a** as discussed above.

A lower panel **64b** of the door **60** is hollow and contains a space into which the insert **64a** can be stored as it is moved downwardly toward the sill **62d**. In this configuration, where the insert **64a** is partly open, a portion of the screen **66a** extends from the screen module **66** and fills the open space between jambs **62b, c** and header **62a**. The remainder of the space between the jambs **62b, c** is filled by a portion of the insert **64a** and the panel **64b**. Thus, the door **60** provides convenient out of sight storage for the insert **64a**.

FIG. 11 illustrates a plurality of alternate coupling members **50-1 . . . 50-6** that could be carried on the movable insert or pane, such as the insert **14c**, and couplable to a free end of the screen fabric **22-1**. As illustrated in FIG. 11, in each instance, the free end of the screen fabric **22-1** would include a coupling element, such as **22-2 . . . 22-7** which would slidably engage the respective coupling member **50-1 . . . 50-6**.

It will be understood that other arrangements can be used to attach a free end of the screen member **22-1** to a moving insert or pane. Alternates or include a spline which would trap the free end of the screen fabric **22-1** in contact with the movable inserts such as **14c** clamps or adhesives. Other variations come within the spirit and scope of the invention.

FIG. 12 illustrates a door **80** which incorporates a screen module **82**, of the type discussed previously, which can be attached to door **84** as an after the fact accessory or add-on.

The module screen 82 can be attached to the door 84 by fasteners 86 in the vicinity of the header 84-1 of the door.

The screen fabric 82-1 can be pulled from the module 82 to close an opening in the door created by moving insert 86 downwardly away from the module 82. A free end 82-2 of the screen material 82-1 is attached to the sash or insert 86. Attachment can be effected by any of the previously discussed methods including using a spline, adhesive, providing attachment clips which slidably engage a portion of the sash of the insert 86. Other attachment vehicles can be used to connect the free end 82-2 to an upper end of the insert or sash 86 without departing from the spirit and scope of the present invention.

As the sash or insert 86 is moved toward the screen module 82, the fabric 82-1 rollably retracts into the module 82 as a result of the internal spring mechanism, discussed above, in connection with door 10. The screen material 82-1, also as discussed above, is under a constant pulling force due to the spring biasing mechanism of the module 82 which continually attempts to retract the fabric 82-1 into the module 82. Thus, as the sash or insert 86 moves toward the module 82, the screen material 82-1 is immediately rolled into the module 82 for out of the way storage.

It will also be understood that a resin or plastic sheet could be used as an alternate to screen fabric 82-1 without departing from the spirit and scope of the present invention. Thus, the screen module 82 provides a mechanism for adding to any existing door, after installation, a retractable screen feature such that existing screen panels or inserts in the door can be removed. This improves convenience and visibility in that with the sash or insert 86 closed, the screen fabric 82-1 is completely retracted and an individual looking at the door looks directly through the glass inserts or sashes without having to look through a screen.

From the foregoing, it will be observed that numerous variations and modifications may be effected without departing from the spirit and scope of the invention. It is to be understood that no limitation with respect to the specific apparatus illustrated herein is intended or should be inferred. It is, of course, intended to cover by the appended claims all such modifications as fall within the scope of the claims.

What is claimed:

1. A door comprising:

first and second spaced apart jambs wherein each jamb carries an axially oriented insert track, an adjacent axially oriented fabric track, and an axially oriented fabric edge retainer;
a spring biased roll of sheet material rotatably carried at one end of the jambs wherein the sheet material is removable from the roll and extends axially along at least part of the jambs with the edges of the sheet material located in respective fabric tracks engaged with respective edge retainers;

wherein the edge retainers each include at least one elongated weather stripping element wherein an edge region of the sheet material slidably engages the weather stripping element; and

wherein the edge retainers each include a second elongated, different weather stripping element spaced from the one weather stripping element wherein an edge region of the sheet material extends laterally between the weather stripping elements.

2. A door as in claim 1 which includes an insert slidably movable in the insert tracks toward and away from respective ends of the jambs wherein the insert is coupled to the sheet material.

3. A door as in claim 2 which includes one of a counterbalance, a latch or friction between the insert and the respective jambs, for slidably supporting the insert at each of a plurality of axially displaced locations along the jambs.

4. A door as in claim 1 which includes one of a counterbalance, a latch or friction between the insert and the respective jambs, for slidably supporting the insert at each of a plurality of axially displaced locations along the jambs.

5. A door as in claim 1 wherein a free end of the sheet material is attached to a sash slidably mounted between the jambs.

6. A door as in claim 5 wherein the free end of the sheet material carries a coupling element which engages a coupling feature of the sash.

7. A door comprising:

first and second spaced apart jambs wherein each jamb carries an axially oriented insert track, an adjacent axially oriented fabric track, and an axially oriented fabric edge retainer;

a spring biased roll of sheet material rotatably carried at one end of the jambs wherein the sheet material is removable from the roll and extends axially along at least part of the jambs with the edges of the sheet material located in respective fabric tracks engaged with respective edge retainers;

wherein a free end of the sheet material is attached to a sash slidably mounted between the jambs; and

wherein the edge retainers each include first and second different strips of weather stripping with one strip having first and second planar sections attached to one another at a selected angle.

8. A door as in claim 7 configured with a portion of the one strip exhibiting an angle in a range of fifteen to seventy-five degrees relative to the extended sheet material.

9. A door as in claim 1 wherein each edge retainer is positioned in a respective fabric track and each includes spaced apart, weather stripping with an edge of the sheet material slidable therebetween.

10. A door as in claim 9 wherein the sheet material has a free end which carries an elongated insert attachment member, L-shaped at least in part, and slidably engageable with an insert.

11. A door as in claim 10 wherein at least part of the insert attachment member has first and second spaced apart ends which extend into and slide between the weather stripping in each fabric track.

12. A door as in claim 11 wherein the sheet material slidably extends between weather stripping, and, if deflected so as to slide out from between the weather stripping, the sheet material can be rotated onto the roll and then re-extended between the weather stripping, by movement of the insert attachment member toward and then away from the roll.

13. A door as in claim 11 wherein the insert attachment member comprises, at least in part, metal or resin.

14. A door comprising:

first and second spaced apart jambs, the jambs are connected at one end by a header and at the other end by a sill wherein each jamb carries an axially oriented insert track, and an axially oriented fabric track; elongated, facing, weather stripping located in each fabric track wherein first and second portions of the weather stripping face one another;

a screen module coupled to the header, the screen module carries a retractable screen having a selected width and having a free end wherein the free end is attached to an

elongated feed assembly that extends at least across the width of the screen and which carries an elongated L-shaped connector element;

an insert carried in and movable in the insert tracks wherein the insert is positionable at a plurality of locations along the jambs and wherein the connector element slidably engages an elongated section of the insert whereby as the insert moves toward the sill the screen is extracted from the module and edges of the screen and ends of the elongated feed assembly slide in the fabric tracks between facing weather stripping portions with the screen retracting into the module as the insert moves toward the header. 5

15. A door as in claim 14 wherein the connector element is formed, at least in part, of one of metal or resin. 15

16. A door as in claim 15 wherein parts of the feed assembly and the connector element are integrally formed.

17. A door as in claim 15 including an elongated plastic body attached to the free end wherein the plastic body has ends that extend between the weather stripping in the fabric tracks. 20

18. A door as in claim 14 wherein in response to an applied lateral force, the screen deflects laterally relative to the jambs, withdrawing, at least in the deflected region, from the fabric tracks and, in the absence of that force, responsive to moving the insert adjacent to the module, the edges of the screen are positioned for re-entry to the fabric tracks, between the weather stripping, as the insert moves toward the sill. 25

19. A door as in claim 14 which carries one of insert 30 latching elements, or, insert counterbalancing elements for positioning the insert at the plurality of locations.

20. A door as in claim 18 which carries one of insert latching elements, or, insert counterbalancing elements for positioning the insert at the plurality of locations.

21. A door comprising:

first and second spaced apart jambs joined by a header and a sill to bound an internal region, each of the jambs carries an insert track and an adjacent generally U-shaped screen track, the insert tracks open toward one another, the screen tracks open toward one another, the screen tracks each carry elongated weather stripping at least some of which extends toward the adjacent insert track; a glass insert, slideable in the insert track toward and away from the header, the insert has an end, closest to the header, which extends between the jambs with an elongated connection region formed on the end and the insert carries latches for engaging the jambs in a plurality of spaced apart locations; a screen module carried adjacent to the header wherein the module includes a biased roll of screen having a free end with the screen and the free end extending between the jambs and the weather stripping in the screen tracks, the free end carrying an elongated engagement feature including an L-shaped member for slidably engaging the elongated connection region formed on the end of the insert such that as the insert moves toward the sill, the screen is extracted from the roll and slides in the screen track between weather stripping with part of the engagement feature extending into the screen tracks, between the weather stripping, and as the insert is moved toward the header, the screen retracts into the module and wherein ends of the engagement feature are located adjacent to at least part of the screen track, when the screen is fully retracted.

22. A door as in claim 21 wherein the L-shaped member comprises one of resin or metal.

ABSTRACT

An exterior door incorporates at least one moving glass insert or sash slidable in first and second spaced apart tracks. An end of the insert is coupled to an end of a spring biased rolled screen. As the insert moves from the roll, the screen is extracted therefrom providing a continuously variable screened region in the door. The insert can be positioned using a counterbalance or spaced apart latchable locations in the door.

EX PARTE
REEXAMINATION CERTIFICATE
ISSUED UNDER 35 U.S.C. 307

THE PATENT IS HEREBY AMENDED AS
 INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS BEEN DETERMINED THAT:

The patentability of claims **14–19** is confirmed.

Claims **1–10** are cancelled.

Claims **11, 20** and **21** are determined to be patentable as amended.

Claims **12, 13** and **22**, dependent on an amended claim, are determined to be patentable.

11. [A door as in claim 10] A door comprising:
first and second spaced apart jambs wherein each jamb carries an axially oriented insert track, an adjacent axially oriented fabric track, and an axially oriented fabric edge retainer;
a spring biased roll of sheet material rotatably carried at one end of the jambs wherein the sheet material is removable from the roll and extends axially along at least part of the jambs with the edges of the sheet material located in respective fabric tracks engaged with respective edge retainers;
wherein the edge retainers each include at least one elongated weather stripping element wherein an edge region of the sheet material slidably engages the weather stripping element;
wherein the edge retainers each include a second elongated, different weather stripping element spaced from the one weather stripping element wherein an edge region of the sheet material extends laterally between the weather stripping elements;

2
wherein each edge retainer is positioned in a respective fabric track and each includes spaced apart, weather stripping with an edge of the sheet material slidable therebetween;

5 *wherein the sheet material has a free end which carries an elongated insert attachment member, L-shaped at least in part, and slidably engageable with an insert; and wherein at least part of the insert attachment member has first and second spaced apart ends which extend into and slide between the weather stripping in each fabric track.*

20. A door [an] as in claim 18 which carries one of insert latching elements, or, insert counterbalancing elements for positioning the insert at the plurality of locations.

21. A door comprising:

first and second spaced apart jambs joined by a header and a sill to bound an internal region, each of the jambs carries an insert track and an adjacent generally U-shaped screen track, the insert tracks open toward one another, the screen tracks open toward one another, the screen tracks each carry elongated weather stripping at least some of which extends toward the adjacent insert track; a glass insert, slidable in the insert track toward and away from the header, the insert has an end, closest to the header, which extends between the jambs with an elongated connection region formed on the end and the insert carries latches for engaging the jambs in a plurality of spaced apart locations; a screen module carried adjacent to the header wherein the module includes a biased roll of screen having a free end with the screen and the free end extending between the jambs and the weather stripping in the screen tracks, the free end carrying an elongated engagement [feature] member including an L-shaped member for slidably engaging the elongated connection region formed on the end of the insert such that as the insert moves toward the sill, the screen is extracted from the roll and slides in the screen track between weather stripping with part of the engagement [feature] member extending into the screen tracks, between the weather stripping, and as the insert is moved toward the header, the screen retracts into the module and wherein ends of the engagement [feature] member are located adjacent to at least part of the screen track, when the screen is fully retracted.
